(57) CLAIM

The ornamental design for a box for oral care products, as shown and described.

DESCRIPTION

FIG. 1 is a perspective view of a box for oral care products, embodying the new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

In the drawings, the broken lines are for the purpose of illustrating portions of the box for oral care products and form no part of the claimed design.
